FIRE ESCAPE

Application filed September 20, 1928. Serial No. 307,153.

This invention is a fire escape and has for its object the provision of a very compact, light, simple and efficient fire escape of the type in which a body-suspending tape or cable is wound upon a drum to be lowered to the ground when the use of the escape is required, and includes means whereby the suspending tape may be rewound to permit its use by another party.

10 In the accompanying drawings:

Figure 1 is a view in elevation, with parts broken away, of a fire escape embodying the present improvements;

Fig. 2 is a horizontal section of the same;

15 Fig. 3 is a vertical section, and

Fig. 4 is a detail section through the brake mechanism on the line 4—4 of Fig. 1.

In carrying out the present invention, there is provided a frame consisting of two side plates 1 and an intermediate plate or partition 2 which are preferably of rectangular form and are secured together by long bolts 3 inserted through their corners and fitted with spacing sleeves 4 between the several parts, as shown clearly in Fig. 3. At the outer sides of the side plates or walls 1 are casing plates 5 which are suitably shaped to project beyond the outline of the frame plates or walls 1 and thereby protect the working parts 20 from damage by chance blows. A driving or main shaft 6 is disposed centrally through the walls or side plates 1 and the partition 2 and is rotatably mounted in suitable bushings, as 7, fitted in the several plates. Between one 25 wall 1 and the partition or intermediate plate 2, a drum 8 is provided, said drum consisting of side plates or disks secured to a hub 9 which is keyed or otherwise fixed upon the main shaft, as shown most clearly in Fig. 3.

30 A steel tape 10 is secured to the hub 9 and is wound thereon between the side plates of the drum, an adjustable belt or loop 11 being firmly secured to the end of the tape, as shown in Fig. 1. This belt may be secured to the

35 tape in any convenient manner and we have shown clamping blocks 12 fitted against opposite faces of crimped portions of the tape, the loop being formed by doubling the tape upon itself and covering the doubled portion with any suitable fabric. A slip ring

13 is mounted upon the loop so as to cause the loop to be tightened around the body of the user and thereby avoid the liability of the user slipping through the loop under the stress of excitement or from accident.

40 The partition or intermediate plate 2 is so located relative to one side plate or wall 1 that the drum will approximately fill the space between the same. Immediately adjacent the intermediate plate or partition and at the side of the same opposite the drum, a gear 14 is loosely mounted upon the main shaft and the hub of said gear has a ratchet face 15 formed thereon, this ratchet face 15 cooperating with the mating face of a ratchet disk 16 which is splined upon the main shaft so that it may slide thereon but is constrained to rotate therewith. Expansion springs 17 are disposed between the ratchet 16 and a pinion 18, secured upon the main shaft 6, and tend to constantly hold the ratchet in engagement with the ratchet face of the gear 14. The pinion 18 is disposed immediately adjacent the side of the wall 1 more remote 45 from the drum and it meshes with a gear 19 fixed upon a counter-shaft 20 which is rotatably fitted in the intermediate plate or partition 2 and the side wall 1, as clearly shown. Upon the outer end of the shaft 20 is secured a gear 21 meshing with a gear 22 which is 50 loose upon the main shaft at the outer side of the adjacent wall 1, as shown in Fig. 3. A flange or hub 23 is secured by rivets or screws to the outer face of the gear 22 and is connected by a ring 24 to the main shaft in such manner that it may rotate about said shaft but cannot move endwise thereon. The hub or flange 23 has threaded connection with a winding crank 25 whereby the re-winding of the tape after use of the same may be very 55 easily and rapidly accomplished. In re-winding the tape, the rotation of the handle or crank 25 is imparted directly to the gear 22 which, of course, effects rotation of the gear 21 and the shaft 20. The gear 19, being fixed upon the shaft 20, will rotate the pinion 18 and the main shaft 6 so that the hub 9 which is fixed to the main shaft will, of course, rotate therewith and re-wind the suspending 60 tape 10. When re-winding the tape, the

ratchet 16 will slip past the ratchet face of the gear 14 but when the tape is un-winding the ratchet will be rotated in the opposite direction and will then engage the ratchet face 15 so that the gear 14 will be rotated to transmit motion to the governor.

The gear 14 meshes with a pinion 26 on a counter-shaft 27 which is mounted in the frame above and at one side of the vertical plane of the main shaft 6 and carries a gear 28, the gear 28 meshing with a pinion 29 which is rotatably mounted upon the governor shaft 30 and is fixed to a governor disk 31. Slidably supported by the outer face of the disk 31 are governor shoes 32 which are provided with radial slots 33 through which headed fastenings 34 are inserted to slidably secure the shoes to the disk, and studs 35 are also inserted through the slots 33 to fit in the disk and thereby maintain the proper alinement of the shoes. Retractile springs 36 are secured by screws 37 to the shoes and bridge the opposed diametric edges thereof so that the springs will hold the shoes out of contact with the brake band until the drum, in un-winding, attains some appreciable speed. The shoes, it will be noted, are semi-circular plates having outstanding flanges on their arcuate edges to engage the brake band. The brake band 38 is a ring or rim provided at intervals with lateral radial lugs 39 through which suitable fastening devices may be inserted to secure the band rigidly to the adjacent wall 1, the uppermost lug being held by the upper bolt 3, as shown clearly in Fig. 3. The inner periphery of the band is preferably lined, as indicated at 40, with some friction material, such as asbestos or the like, which when engaged by the respective governor shoes will serve to retard the rotation of the working parts and thereby check the descent of the person using the escape so that violent dropping to and impact with the ground will be avoided.

Having thus described the invention we claim:

A fire escape comprising a frame including a pair of side walls and a partition between and parallel with the side walls, a main shaft 50 extending through the frame, a drum secured on said shaft between one side wall and the partition, a gear disposed between the partition and the other side wall of the frame and fixed to the shaft, a governor arranged adjacent the last-mentioned side wall of the frame, a train of gearing connecting the shaft with the governor and including a gear loose upon the shaft, a ratchet rigid with the side of said loose gear, a mating ratchet slidably 55 mounted on the shaft and constrained to rotate therewith, expansion springs between the fixed gear and slidably mounted ratchet and tending constantly to hold the two ratchets in engagement, a winding handle 60 mounted on the shaft and constrained to rotate therewith, a pinion rigidly 65 fitted on the shaft, a pinion rigid

with said handle and held against movement endwise of the shaft, and gearing connecting said pinion with the gear which is fixed to the main shaft.

In testimony whereof we affix our signatures.
